TOY SPACE SHIP

Ralph G. Rowland, New York, N. Y., Howard Carroll, Ridgefield, N. J., and Edwin H. Wegman, Freeport, N. Y., assignors to The S. J. Wegman Company, Lynbrook, N. Y., a copartnership

Application October 17, 1955, Serial No. 38,423

Term of patent 7 years

(Cl. D34—15)

Fig. 1 is a plan view of a toy space ship showing our new design, and

Fig. 2 is a side view thereof.

The opposite side, not shown, has substantially the same appearance as the side shown in Fig. 2.

We claim:

The ornamental design for a toy space ship, substantially as shown and described.
